TELESCOPIC UMBRELLA FRAME

Arno Zierold, Floha, and Karl Kortenbach, Solingen-Weyer, Germany, assignors to Kortenbach & Rauh Kommanditgesellschaft, Solingen-Weyer, Germany

Application May 2, 1936, Serial No. 77,632
In Germany August 1, 1935

11 Claims. (Cl. 135—26)

The invention relates to a telescopic umbrella frame.

Whereas in the known collapsible umbrella frames the lower rib parts are pivotally attached to the upper ones, so that they can be folded over into the parallel position, according to the application half of each rib is slideable on the other half, so that the entire umbrella frame can be collapsed telescopically. In the extended position the extensible parts are capable of being locked with respect to one another in the manner of a bayonet catch. Considerable simplifications as regards the manufacture and the manipulation of the umbrella frame according to the invention thus result.

According to the invention, in a telescopic umbrella frame sleeves, to which the spreaders are pivotally attached and in which the outer rib parts are fixed, are capable of being slid on the inner rib parts until they strike against a projection on the inner rib parts. This projection, when in the position in which it strikes, is opposite a recess, for instance in the outer rib parts, so that, by turning the runner with respect to the top notch, the projection can enter this recess.

The invention is illustrated by way of example in the accompanying drawing, in which

Fig. 1 shows in elevation the umbrella frame according to the invention in the position of use, the outer ribbed parts being locked together,

Fig. 2 a detail of Fig. 1 to a larger scale but showing the outer ribbed parts not locked together,

Fig. 3 a detail of Fig. 2 in side elevation,

Fig. 4 to a smaller scale the umbrella extended, but not opened,

Fig. 5 to a larger scale a cross-section of the inner telescopic tube,

Fig. 6 partly in elevation and partly in section the arrangement for limiting the extension of the telescopic tubes of the umbrella stick,

Fig. 7 the arrangement according to Fig. 6 in another view,

Figs. 8 and 9 in elevation and longitudinal section respectively the lower end of the inner telescopic tube and

Figs. 10 and 11 the umbrella handle in section.

1 is the inner and 2 the outer telescopic tube. The tube 1 has a pressed-in longitudinal groove 3 in which the tube 2 is guided by means of a projection 4 which is made by the material being pressed out inwards. The extending is limited by an arrangement to be described hereinafter. On 55 the telescopic tube 1,2 a sleeve-like sliding mem-

ber 5 is guided, to which the runner 6 is fixed; to the latter the lower ends of the spreaders 7 are tied in a known manner. The sleeve member 5 is slightly flared at the bottom, in order that, when the umbrella is being closed the projection 8 is gently pressed inward and thereupon secures by its spring the sliding member when the umbrella is closed in a known manner against a longitudinal and transverse motion. For securing the sleeve member in the upper position a further catch 9 of a kind known per se is provided.

At the upper end of the inner telescopic tube the top member 10 is fixed to which the ribs are tied in a known manner. Above the top member the umbrella point 11 is fixed.

The ribs consist of inner parts 12 of circular cross-section and outer parts 13 of U-shaped cross-section. On the parts 12 is slideable a sleeve 14, to which (see more particularly Fig. 2) the spreaders 7 are pivotally attached with their outer ends to lugs 15, as will be seen from the drawing. The outer rib parts 13 are slid into the sleeve from the outside and are fixed at the connecting end by the sleeve being compressed.

In the constructional example shown the outer rib parts 13 have a recess 16, opposite which, when the umbrella is open (see Fig. 1), a corresponding projection 17 of the inner rib parts is disposed. As will be seen from Fig. 3, the projection is formed by bending out the material of the inner 30 rib parts. The purpose of the projection and of the recess will be described hereinafter.

According to Figs. 8 and 9 the arrangement for limiting the extending motion of the telescopic tubes consists of a substantially U-shaped leaf spring 18, the limbs of which are of different length and are provided with buttons. The button 19 of the shorter limb rests in a hole of the inner tube and extends through the tube to such an extent that it can enter a corresponding hole 40 of the outer tube (see Fig. 6). The button 20 of the longer limb rests in a corresponding hole in the middle of the groove 3. The button 19 is calotte-shaped externally.

Immediately above the button 20 the inner 45 telescopic tube has a rectangular excision 21, the length of which corresponds to the projection 4. Consequently the two telescopic tubes can be turned with respect to one another through an angle which corresponds to the width of the 50 slot and is about 45°. The button 19 does not hinder this rotary motion, as it is only about as high as corresponds to the wall thickness of the two tubes. As will be seen from Fig. 6, only the calotte of the button 19 projects slightly beyond 55

the corresponding hole of the outer telescopic tube, so that only slight resistance is offered to a turning motion.

In order to open the umbrella, the telescopic stick and rib parts must first be extended. This is effected by holding the umbrella point or tip with one hand and the umbrella handle with the other hand and then exerting a pull with both hands in opposite directions. The extending motion is limited in such a manner that the projection 4 of the outer tube 2, which is guided in the groove 3, bears against the button 20 of the U-shaped spring 18 of the inner tube 1 (Fig. 6) and the button 19 of the spring 18 enters a corresponding hole of the outer tube 2. In this extended position of the umbrella frame, the projection 4 of the tube 2 is next to the excision 21 of the tube 1 and the projection 17 of the parts 12 are next to the corresponding excisions 16 of the parts 13 so that a locking can take place by a relative turning of the parts. If the umbrella handle 22, which is only axially displaceable on the telescopic tube, and the umbrella point or tip are turned in the direction of the arrow according to Figure 4, the spring catch 8 of the tube 2 lying in the corresponding excision of the sliding member 5, the projection 4 will be locked in the excision 21 and the projections 17 will be locked in the excisions 16 because the rotary motion is transmitted from the sliding member 5 over the spreaders 7 to the sleeves 14 and the outer rib parts 13 connected therewith. During the turning motion, the calotte-shaped button 19 passes out of its hole in the outer tube. The U-shaped spring presses it against the inner wall of the outer tube 1 so that the telescopic parts are held in the locked position by friction.

The umbrella may be folded like an ordinary umbrella.

For holding the free ends of the outer rib parts in the telescoped position the following arrangement is provided.

The umbrella handle 22 is formed like a bell, the rim 23 of which is at such a distance from the umbrella stick that the free ends of the outer rib parts 13 can enter the cavity. A sleeve 24, to which the umbrella handle is fixed, is slideable on the outer telescopic tube 2 and is secured against rotation with respect to the latter through a pin 25 which is riveted at one end and is slideable in a slot 26 of the outer telescopic tube. The length of the slot determines the distance through which the handle can be slid. For preventing unintentional movement of the umbrella handle a substantially U-shaped leaf spring 27 is slid over the pin, the limbs of which are fixed at 28 to the outer telescopic tube. The middle part of the leaf spring is compressed to an extent corresponding to the length of the slot 26. From Figs. 10 and 11 the position of the pin 25 with respect to the leaf spring in the two extreme positions will be seen.

For facilitating the assemblage of the telescopic tubes holes 29, 30 (Fig. 7) are bored above and below the projection 4, for enabling a fork-shaped tool to be inserted, which presses the button 20 in to such an extent that, on the outer telescopic tube being slid over, the projection 4 will pass over it.

The constructional form illustrated and described is only a constructional example. Many modifications are possible within the scope of the invention. More particularly it is possible to arrange the parts oppositely to the manner shown.

What we claim is:—

75 1. An umbrella frame comprising in combina-

tion a telescopic umbrella stick, a sliding member adapted to move along said umbrella stick, telescopic ribs comprising inner and outer sections, spreaders connecting said outer sections to the umbrella sliding member and cooperating means on said inner and outer sections for simultaneously locking all the extended outer rib sections to the inner rib sections before the movement of the sliding member for opening the umbrella frame, the locking means consisting of a slot and pin connection.

2. An umbrella frame comprising in combination a telescopic umbrella stick, a sliding member adapted to move along said umbrella stick, telescopic ribs comprising inner and outer sections, spreaders connecting said outer sections to the umbrella sliding member and cooperating means on their inner and outer sections for simultaneously locking all the extended outer rib sections to the inner sections before the movement of the sliding member for opening the umbrella frame, the locking means consisting of a slot and pin connection said sliding member being rotatable on the longitudinal axis of the umbrella stick through a predetermined angle for actuating said pin and slot connection for effecting locking engagements.

3. An umbrella frame comprising in combination a telescopic umbrella stick, a sliding member adapted to move along said umbrella stick and being rotatable thereon, telescopic ribs comprising inner and outer sections, spreaders connecting said outer sections to the umbrella sliding member and cooperating means on said sections for simultaneously locking the extended outer rib sections to the inner sections before the movement of the sliding member for opening the umbrella frame, the locking means consisting of a slot and pin connection adapted to be actuated by the sliding member, and means for limiting the rotation of said sliding member to a predetermined angle for effecting locking engagement of the pin and slot connections.

4. An umbrella frame comprising in combination a telescopic umbrella stick, the telescopic parts thereof comprising one section having a longitudinal recess formed therein and another section having an inwardly directed projection engaging said recess, telescopic ribs comprising inner and outer sections, a sliding member adapted to move along said umbrella stick, spreaders connecting said outer rib sections to the umbrella sliding member and means on said rib sections for simultaneously locking the extended rib sections by turning said sliding member before the longitudinal movement of the sliding member for opening the umbrella frame takes place.

5. An umbrella frame comprising in combination a telescopic umbrella stick, telescopic ribs comprising inner and outer sections, a sliding member adapted to move along said umbrella stick, the outer telescopic section of the ribs having a U-shaped cross-section, spreaders connecting said U-shaped outer rib sections to said umbrella sliding member and means for simultaneously locking the extended outer U-shaped rib sections on their inner ends to the inner rib sections by turning said sliding member before the longitudinal movement of the sliding member for opening the umbrella frame.

6. An umbrella frame comprising in combination a telescopic umbrella stick, telescopic ribs comprising inner and outer sections, one telescopic section of the ribs having a U-shaped cross-section and the other part a round cross-section,

- a sliding member adapted to move along said umbrella stick and to turn thereon, spreaders connecting the parts having a U-shaped cross-section to the umbrella sliding member, and
- 5 means for simultaneously locking the extended outer rib sections on their inner ends before the longitudinal movement of the sliding member for opening the umbrella frame, the locking means comprising an incision in the telescopic
- 10 section of U-shaped cross-section and a hump formed on the telescopic part of round cross-section to interlock with said incision.
7. An umbrella frame comprising in combination a telescopic umbrella stick, sleeve-like parts
- 15 on the outer ribs, a sliding member adapted to move along said umbrella stick, telescopic inner and outer rib sections, spreaders connecting said outer rib sections to the umbrella sliding member, and engaging with said sleeve-like parts of the outer
- 20 rib sections, and means for simultaneously locking the extended outer rib sections on their inner ends to the inner rib sections before the longitudinal movement of the sliding member for opening the umbrella frame.
- 25 8. An umbrella frame comprising in combination a telescopic umbrella stick, a sliding member movable along said umbrella stick, telescopic inner and outer rib sections, spreaders connecting said outer ribs to said umbrella sliding member, means
- 30 for simultaneously locking the extended outer rib sections on their inner ends to the inner sections before the longitudinal movement of the sliding member for opening the umbrella frame takes place and means for holding the locked outer rib
- 35 sections in locked position.
9. An umbrella frame comprising in combination a telescopic umbrella stick, a sliding member adapted to move along said umbrella stick, telescopic inner and outer rib sections, spreaders connecting said outer rib sections to said umbrella sliding member, and means for simultaneously locking the extended outer rib sections on their

inner ends to the inner sections before the longitudinal movement of the sliding member for opening the umbrella frame, said locking means consisting of a slot and pin connection adapted to be actuated by means of said sliding member being turned on the longitudinal axis of the umbrella stick through a predetermined angle, and means on said umbrella stick for limiting the turning movement of the sliding member when the outer rib sections are in locked position.

10. An umbrella frame comprising in combination a telescopic umbrella stick, a sliding member adapted to move along said umbrella stick, telescopic inner and outer rib sections, spreaders connecting said outer sections to said sliding member, means for simultaneously locking the extended outer rib sections on their inner ends before the longitudinal movement of the sliding member for opening the umbrella frame, means for holding the locked outer rib sections in the locking position and means for holding the free ends of the locked outer rib sections in the position corresponding to the closed position of the umbrella.

11. An umbrella frame comprising in combination a telescopic umbrella stick, a sliding member adapted to move along said umbrella stick, telescopic inner and outer rib sections, spreaders connecting said outer rib sections to said umbrella sliding member, means for simultaneously locking the extended outer rib sections on their inner ends to the inner sections before the movement of the sliding member for opening the umbrella frame, means for holding the locked outer rib sections in the locking position, said means comprising an umbrella handle adapted to slide relatively to the umbrella stick and having means for holding the free ends of the locked outer rib sections in the position corresponding to the closed position of the umbrella.
